UNITED STATES PATENT OFFICE.

H EUGENE CHUBBUCK, OF PEORIA, ILLINOIS.

ROUTE-SIGN FOR STREET-CARS.

1,142,491.

Specification of Letters Patent.

Patented June 8, 1915.

Application filed March 6, 1913. Serial No. 752,283.

To all whom it may concern:

Be it known that I, H EUGENE CHUBBUCK, a citizen of the United States, residing at Peoria, in the county of Peoria and State of Illinois, have invented certain new and useful Improvements in Route-Signs for Street-Cars, of which the following is a specification.

My invention has reference to destination or route signs for street cars.

One of the objects of the present invention is to combine in a single unitary structure a destination or signal panel on which is painted a large character denoting the route of the car, said character being very conspicuous and readable at a great distance during daylight, and the area of said painted portion of the character is perforated with suitable size perforations, whereby, during the hours of darkness, when said sign is in use, rays of light may shine through said character, illuminating the same, making it conspicuous and readable at a considerable distance, said panel also having painted thereon beneath said large character, the name of the street which marks the route of the car, or the name by which the car is known, and which said character represents, the letters of said name being perforated, whereby, during the hours of darkness, said name will be legible in like manner as said large and bold character.

The preferred embodiment of this invention is fully illustrated in the accompanying drawings, in which:

Figure 1 is a perspective view of my improved sign, the same being shown mounted on one corner of a car roof; Fig. 2 is a cross section in plan as the same would appear if taken on the line 2-2 of Fig. 1; Fig. 3 is a plan view of the sign structure, a portion of its top plate broken away, and Fig. 4 is a face view of one of the plates of the sign on which the destination or route character and names are placed.

The sign is made up in the form of a triangular shaped box 1, the right angular face portions 2 and 3 of which, face respectively, to the front and side of the car, see Fig. 1. The box 1 comprises the corner angle iron uprights or supports 4, 5, and 6, which at their lower ends are split as at 7, producing the feet 8 adapted to be suitably secured to the roof A of a car for supporting said box in position. The angle iron upright or support 5 is braced by the inner smaller angle

iron upright or support 9, which also serves as a spacing member and to which is secured the further and inner angle iron upright or support 10. As shown, between the uprights 5 and 10 guideways 11 are arranged, forming run-ways for panels, to be described, which are removably and interchangeably arranged on said box.

The angle iron uprights or supports 4 and 6 are braced by the inner angle iron uprights or standards 12, which are so connected to said angle iron uprights 4 and 6 as to provide the guideways 13 forming run-ways for the opposite edges of the panels 15 aforesaid, which also have a removable and interchangeable relation with said uprights or standards 4 and 6. The corner uprights or standards 4, 5 and 6 and associated bracing structure are united or braced by the angle iron band 14. This band is removed a suitable distance above the feet 8 of said standard and at 15 is cut away to adapt the band to embrace said uprights or standards 4, 5 and 6, as best seen in Fig. 2. 16 is an additional angle iron part forming the lower connecting structure for said uprights, being secured to the uprights or standards 4 and 6. To the underside of the horizontal flat faces of said angle iron band 14 and said angle iron part 16 is secured a plate 17, which may be termed the bottom of the box 1. Plates 18 and 19, Fig. 1, connected respectively to the standards 5 and 6 and 5 and 4, serve as aprons to complete the facing front 80 and side portions of the box.

At the upper ends of the uprights or standards 4, 5 and 6, an angle iron brace member 20 is provided, connecting said parts in manner seen in Fig. 3, and completing the upper bracing structure, is an angle iron part 21 connecting the uprights 4 and 6. The top 22 of the box is laid on and suitably secured to the horizontal flat faces of the parts 20 and 21, see Fig. 3. A back plate 16^a 100 is secured to the lower angle iron part 16 and upper angle iron part 21.

23 are signal panels, both of which have a removable or interchangeable relation with the uprights or standards of said box. One 105 of said panels, serves as the front panel, facing the direction in which the car is moving, and said panel is slidably carried in the grooves or run-ways 11 and 13 of said box, while the other panel serves as the side panel, 110 facing the curb or side of the street, and said panel is also slidably carried in the similar

grooves or run-ways 11 and 13 of said box. The panels are duplicates of each other and the description of one will suffice for both. Each has knobs or hand holds or grips 24, 5 by means of which a person may remove or place a panel or panels.

On the panel 23 is painted a large and bold character, preferably a letter, designated 25. In this instance the character 25 10 is the letter "W" representing the name "West Bluff" which is also painted on the panel, beneath the letter "W". It is obvious that the letter may represent any name, such as will designate the destination or route of 15 the car or be the name by which the car is more generally known, as for instance, "K" standing for "Knoxville".

The area or surface of the panel covered by the letter or character is perforated, as 20 at 26. In other words the character or letter is not only painted on the panel, but is also an open or perforated character or letter. I paint the letter black and the size of 25 such letter has been determined by experiments, and the same may be read during the day-light at a distance of an ordinary city block. The perforations 25 are of a suitable size and uniformly arranged, so that said 30 perforations, when a light is caused to shine through the same, conspicuously discloses to the pedestrian for the distance of approximately a city block, what the letter is. In this way the letter is legible at a considerable distance during the day and also legible 35 during the night. A light may be provided, by placing an incandescent light at a suitable place within the box, not shown, and wired in any suitable manner. The name beneath the letter, which denotes the destination 40 or route of the car, or the name by which the car is familiarly known, is also painted in black, and the letters need only

be of such a size as to be legible at a reasonable distance, so that, a person who is not familiar with the route of the car, as designated by the letter, which as stated, represents the name by which the car is known, may easily and quickly select his car to reach the destination he may seek. The name being in black is easily readable for a reasonable distance during daylight, and that it may be legible for a reasonable distance at night, each letter of the name be it "West Bluff", "Knoxville" or some other name, is 50 an open or perforated character, through 55 which the light may shine.

I do not cover the perforations or use any color scheme, except that I paint the letters black. There being no covering over the perforations and no glass being used there 60 is absolutely no chance of the letter being blurred during rain or snow, and thereby destroy the function of the sign during the night time. The letter and the name, which the letter represents, being continued in one 65 unitary structure and arranging the same as shown, they are both directly in the line of vision when a person is endeavoring to discern his particular car and he is thereby enabled to locate the car much more quickly 70 than ever before.

What I claim is:-

A route sign for street cars, including a member, said member having a route indicating name thereon, and a character representing an abbreviation of the name and being of a size considerably greater than that of the name. 75

In testimony whereof I affix my signature, in presence of two witnesses.

H EUGENE CHUBBUCK.
